UNITED STATES PATENT OFFICE.

AMOS L. GRINNELL, OF CAMPBELL, IOWA.

ELEVATED CABLE RAILWAY AND CAR.

SPECIFICATION forming part of Letters Patent No. 416,220, dated December 3, 1889.

Application filed November 6, 1888. Serial No. 290,141. (No model.)

To all whom it may concern:

Be it known that I, AMOS L. GRINNELL, a citizen of the United States of America, and a resident of Campbell, in the county of Polk 5 and State of Iowa, have invented an Elevated Cable Railway and Car, of which the following is a specification.

My object is to establish double-tracked elevated lines of travel, and to propel cars 10 thereon in suspended positions in such a manner that persons can speedily go from one place to another over direct routes built through farms and over roadways.

My invention consists in the construction 15 and combination of cables and cable supports and carriages having traction-wheels on their tops, as hereinafter set forth, pointed out in my claims, and illustrated in the accompanying drawings, in which—

20 Figure 1 is a perspective view of a section of my elevated double track, showing a carriage suspended thereon and in position as required for practical use. Fig. 2 is a modified form of the double track. Fig. 3 illustrates a device for pivoting the tracks to the 25 posts to facilitate the passage of a car over the point where the track-support projects at right angles from the post.

A are posts set in the ground at suitable 30 distances apart.

B are cross-pieces fixed to the top portions of the posts.

C are cables fixed to the ends of the cross-pieces B in such a manner as to maintain a 35 continuity of track-surface, over which traction-wheels can be advanced.

D (shown in Fig. 1) is a cable stretched over and fastened to the top of the posts to brace them and to aid in supporting the cables C, that are connected therewith by means 40 of stay rods or ropes f, that extend from the cross-pieces B to the cable D.

G (shown in Fig. 2) represents a curved bar fixed to the ends of the parallel cables C 45 to connect them in such a manner that a carriage can be moved from one cable to the other, as required in making a continuous track or a turn in a track.

J are rigid bearers pivoted to the ends of the cross-pieces B in such a manner that the track can be fixed on their beveled top edges, so that when the suspended carriage reaches

one end of the bearer J it will depress that end, and the bearer will serve as an inclined plane to facilitate the passage of the carriage 55 over the point of the track-support, and when the carriage has passed the pivotal point and center of the bearer it will reverse the motion of the bearer and serve as an inclined plane to advance the carriage on the track. The 60 short and abrupt inclines of a track that is supported at a fixed point at a post, and caused by the sagging and yielding of the track or cable, is avoided by means of the pivoted bearers J. 65

H represents a car or carriage that has its traction-wheels on top, as shown in Fig. 1. The tread or periphery of each wheel has a continuous groove adapted to admit the cable upon which it is to be suspended and propelled. Any suitable mechanism may be combined with the carriage for the purpose of rotating one or both of the wheels as required to propel the suspended carriage upon the elevated track. 70

I am aware cables have been supported in parallel position upon a line of posts and that a seat has been suspended upon an elevated track or cable in such a manner that a person upon the seat could operate mechanism 80 to propel the seat and a car on top of the cable; but my manner of constructing a continuous track of parallel cables and rigid curved ends is novel and advantageous. 75

I claim as my invention—

1. An improved elevated cable railway comprising a line of fixed posts having fixed cross-pieces at their top portions, rigid track-bearers pivoted to the ends of said cross-pieces, a rigid curved track at the end of the 90 line of posts, and two parallel cables connected with the ends of the curved track and the pivoted track-bearers, to operate in the manner set forth, for the purposes stated.

2. In an elevated railway-track or cable- 95 support, the combination of pivoted rigid support J with a cross-piece fixed to a post, to operate in the manner set forth, for the purposes stated.

AMOS L. GRINNELL.
